(57) **CLAIM**

The ornamental design for a construction machine as shown and described.

DESCRIPTION

FIG. 1 is a front view of a construction machine of our new design.

FIG. 2 is a rear view thereof.

FIG. 3 is a left view thereof.

FIG. 4 is a right view thereof.

FIG. 5 is a top view thereof.

FIG. 6 is a bottom view thereof; and,

FIG. 7 is a top, rear, right perspective view thereof.

The inventors and Applicant reserve the right to disclaim any individual features (e.g., edge, surface, protrusion, recess, curvature, color, or any other feature), portions of features, or combinations of features, for example, by illustrating such features, portions, or combinations thereof in broken lines, without shading, and/or as faded or blurred as compared to claimed features. The portions of the construction machine shown in broken lines form no part of the claimed design.
